UNITED STATES PATENT OFFICE.

FORREST B. MACNAB, OF DAYTON, OHIO, ASSIGNOR TO THE DAYTON ENGINEERING LABORATORIES CO., A CORPORATION OF OHIO.

SYSTEM OF ELECTRICAL DISTRIBUTION AND CONTROL.

1,172,221.

Specification of Letters Patent.

Patented Feb. 15, 1916.

Application filed December 26, 1912. Serial No. 738,647.

To all whom it may concern:

Be it known that I, FORREST B. MACNAB, a citizen of the United States, residing at Dayton, county of Montgomery, and State 5 of Ohio, have invented certain new and useful Improvements in Systems of Electrical Distribution and Control, of which the following is a full, clear, and exact description.

10 This invention relates to an improvement in systems of power distribution and control, and particularly to systems of this character, which are employed in conjunction with internal combustion or explosion engines.

One of the primary objects of the present invention is to provide a system of devices 20 for imparting power to the engine to start or make the same self-actuating and to receive power from said engine when the same becomes self-actuating, to store up power to be used in future starting operations, wherein a main operating member is capable of controlling the associated instrumentalities of the system of devices for effecting the transmission of power to start the engine and the transmission of power from the engine to a storage source.

In systems similar to those which are 25 described, claimed and illustrated in the co-pending applications of Charles F. Kettering, filed June 15, 1911, Serial No. 633,443; filed September 19, 1912, Serial No. 721,237, there is provided a starting device or machine, normally disconnected from the engine but having coupling mechanism so arranged that it may be shifted to connect the engine and starting device together. There is also provided a means for imparting 35 a slow initial movement to the starting device or machine, to facilitate the coupling up of the engine and starting device, which, of course, must take place previous to or concurrently with the shifting of the coupling mechanism. The systems described 40 in the above mentioned co-pending applications also include certain connections between the starting device and the source of power supply, which must be shifted to permit the operation of the starting device 45 for initially actuating the engine.

Another object of the present invention is to combine a starting device or system of the above mentioned type and an ignition 50 system, for the prime mover or engine, with

a main operating member, so that said member will be capable of effecting not only the functions incident to bringing the starting system into operation to start the engine, but will also effect the establishment 60 of the ignition system or systems, either concurrently with or in any desired timed relation, relative to the bringing of the starting system into operation to start the engine.

It is well known that certain types of 65 ignition systems embody characteristics which make them peculiarly efficient for use during the starting operation of engines, while certain other types of ignition systems embody different characteristics 70 which better adapt them for furnishing ignition, after the engine has become self-actuating.

As an illustration of the above, it is well known that ignition of the vibrating spark 75 type is peculiarly efficient during the starting operation of the engine, because of the quick succession of sparks which occur for each time that the circuit is closed. However, it is equally well known that it is not 80 advisable to employ the vibrating spark type of ignition for ordinary running purposes, inasmuch as the current consumption in a system of this type is excessive and does not, as a matter of fact, give any 85 greater efficiency than other types of ignition systems which are much more economical.

In the co-pending applications of Charles F. Kettering, filed September 15, 1909, Serial 90 No. 517,788; filed March 12, 1910, Serial No. 548,921; and in the co-pending application of Charles F. Kettering and William A. Chryst filed November 20, 1912, Serial No. 732,483; there is described, claimed and 95 illustrated systems wherein ignition of the vibrating spark type may be brought into use for certain purposes, which are more efficiently met by ignition of this type, in combination with certain types of what is 100 known as single spark ignition and which is, as has been described in the aforementioned co-pending applications, the preferred type of ignition for ordinary running purposes.

In the present invention, a plurality of different ignition systems are provided, in combination with a starting system, which may be similar to that disclosed in the co-pending applications of Charles F. Ketter- 110

ing, filed April 17, 1911, Serial No. 621,512; filed June 15, 1911, Serial No. 633,443; and filed September 19, 1912, Serial No. 721,237; wherein a main operating member is provided for controlling the starting system and which is also capable of establishing ignition systems of the vibrating and single spark type of ignition, concurrently with, or previous to, the operation of the starting system, to start the engine. However, in order to conserve the source of current which supplies the vibrating spark system, the provisions which are operated by the main operating member, to bring said vibrating spark system into operation, are only maintained in position to establish this ignition system during the period that the main operating member is maintained in position to cause the operation of the starting device. However, the provisions which are operated by this main operating member for establishing the single spark type of ignition, are held in such position as to provide ignition of this type, by certain coöperating elements which will maintain this system in established condition for such time as is desired, regardless of the movement of the main operating member, to cut out the starting operation of the starting device and to also dis-establish the vibrating spark system.

A further object of the present invention is to provide certain of the elements for controlling the different systems of ignition, which may be operated independently or concurrently with the main operating member.

A still further object of the present invention resides in the provision of a controlling element for starting systems for engines, in combination with a positive locking mechanism, which will maintain said operating member in inoperative position, said locking mechanism being inoperative when the operating member is in other than its normal position.

Further objects and advantages will be apparent from the following description, reference being had to the accompanying drawings, wherein a preferred form of one embodiment of the present invention is clearly shown.

In the drawings: Figure 1 is a diagrammatic view of the electrical circuits and connections embodied in the present invention. Fig. 2 is a perspective view of a casting, wherein certain of the controlling elements are mounted. Fig. 3 is a view in rear elevation of the switch unit comprising the contact arms and supporting plate, which are normally contained within the casing shown in Fig. 2. Figs. 4 and 5 are detail views, partly in section, of the releasing and locking elements embodied in the present invention. Fig. 6 is a detail perspective

view of one of the elements embodied in the locking and releasing structure. Fig. 7 is a view, partly in section, illustrating the mechanical arrangements of the controlling and shiftable elements of the ignition and starting systems. Fig. 8 is a detail view of the joint or connection between the coöperating elements of the main operating member. Figs. 9 and 10 are detail views of different forms of the arm for connecting the ignition controlling elements with the main operating member.

In the present embodiment, there is included a self-starting system for combustion engines, which embodies certain features included in the co-pending applications of Charles F. Kettering, filed June 15, 1911, Serial No. 633,443, and filed September 19, 1912, Serial No. 721,237; and also ignition systems embodying a plurality of different types, certain features of some of which have been described in the co-pending applications of Charles F. Kettering, filed March 12, 1910, Serial No. 548,921, and filed November 20, 1912, Serial No. 732,483; and the U. S. Patent No. 1,040,349 to Charles F. Kettering.

Heretofore, as a general rule, it has been necessary to operate a plurality of different elements, independently of each other, in order to effect the starting of the engine and the maintenance thereof, in operation, under its own power. However, the present system not only effects the starting operation of the engine, but also the ignition thereof, by the operation of a main operating member which may be further arranged to accomplish a series of functions which are advisable and necessary to secure the most advantageous results, from a combination of systems of the type set forth.

In starting systems similar to the types set forth in the above mentioned co-pending applications and patent, it has been found advantageous to effect a slow initial movement of the starting machine or device, previous to the transmission of power to said machine to cause the same to crank or start the engine. This affecting of the slow initial movement of the starting device, has for its purpose to facilitate the connection of the engine and starting device.

In the co-pending applications of Charles F. Kettering, filed June 15, 1911, Serial No. 633,443, and filed September 19, 1912, Serial No. 721,237, there is shown a controlling element for a starting system, which preferably comprises the engine clutch pedal which, besides having its normal function of controlling the position of the engine clutch, also, under certain conditions, controls the starting system. However, as has been explained in these co-pending applications, it is first necessary to operate a supplemental element, spoken of as a push but-

ton switch, for closing a supplemental circuit which effects the coupling up of the clutch pedal and the shiftable connections of the starting device. This connection between the clutch pedal and the shiftable connections of the starting device, is accomplished by the operation of what is termed, a clutch magnet. In order to simplify the construction as much as possible, this clutch magnet was placed in series with the circuit which transmitted power to the starting device, to effect the slow initial movement thereof. In the present invention, as will be seen hereinafter, this starting clutch magnet has been entirely dispensed with, as well as the push button switch, while the clutch pedal is used only to perform its normal functions of controlling the engine clutch.

Referring to the diagrammatic view of the drawings, the numeral 20 designates a dynamo-electric-machine, being shown in the present instance as comprising a generator 21, and a motor 22, preferably so combined that they form but a single unit. Of course, from all intentions of the present invention, this dynamo-electric-machine may either be of that type shown and described in the co-pending application of Charles F. Kettering, filed September 19, 1912, Serial No. 721,237, or of the type shown and described in the co-pending application of Charles F. Kettering, filed June 15, 1911, Serial No. 633,443, or as a matter of fact, the dynamo-electric-machine may be entirely dispensed with and a simple electric motor may be employed in conjunction with a storage battery, to give the starting power.

The motor shown in the present invention is of the series wound type, and when in operation through the shifting of the switch 25, has the following circuit: from the storage battery 29, the current flows through the wire 28, common switch rod 27, brush 26, rod 24, through wire 23, series winding 31, through the motor 22 and back to the battery, via wires 32 and 30. However, it will be noted that normally this circuit is broken by the position of the switch brush 26, which, when the electric machine is of type shown in the co-pending application of Charles F. Kettering, filed September 19, 1912, Serial No. 721,237, normally closes the generator circuit in the manner fully described in said co-pending application.

When the electric machine is being employed as a generator to store up power in the accumulator 29 for future starting operations, or to furnish current for any desired work circuits, the sliding switch plate 26 will be in the position shown in Fig. 1. In order to prevent the accumulator 29 from charging back through the sliding switch element to the generator armature and field windings, at such times as the voltage of the

across the brushes of the generator, a cut-out relay device is included in the generator circuit and is of such construction that when the voltage of the generator falls below that of the battery, the main circuit will immediately be opened and maintained in open condition until the voltage of the generator rises above the voltage of the accumulator. This cut-out relay device comprises a fine winding 34 which is directly across the generator circuit, and is of such construction that as soon as the voltage of the generator has risen to a predetermined point, (preferably a little above the battery voltage), the contacts 36 and 37 will be closed, thus permitting current to flow through the main line of the generator to the battery for charging purposes.

A detailed description of the generator circuit will now be given. As soon as the generator starts to build up, current will flow across the armature 21, through brush 98, wires 10 and 11, fine wire coil 34 to the opposite side of the line, by means of the wire 12. Now, as soon as the voltage builds up sufficiently in the coil 34, the contacts 36 and 37 will be closed, so that the current from the generator will flow through the coarse winding 35 of the relay, through contacts 37 and 36, directly to the battery, via wires 13 and 30.

A description of the ignition systems embodied in the present invention, will not be given in detail, in the present application, inasmuch as these systems were fully described and shown in connection with the co-pending application of Charles F. Kettering and William A. Chryst, filed November 20, 1912, Serial No. 732,483.

In the present system, an ignition switch 105 is embodied, wherein a plurality of controlling elements are so arranged that they may be operated independently of each other, to establish ignition systems of different types independently, or they may be operated in certain combinations to provide ignitions of different types concurrently.

The internal structure of the switch mechanism, that is, the arrangement of the contacts, detent and supporting elements, is substantially the same as described in the above mentioned co-pending application and will not be referred to in detail herein, except wherein this structure relates specifically to the present invention. However, in the present invention, I have combined with an ignition system of the type set forth in the above mentioned co-pending application a main operating member which may be actuated in any desirable manner, in the present instance, there being shown a plate to facilitate the operation thereof by foot, and a handle which may be used when it is desired to operate the same manually.

This operating member comprises either 130

the plate 40 or the handle 41, which is shown in dotted lines, secured to the rod 42 in any suitable manner. The rod 42 passes through a bearing 43, preferably mounted in the center of the ignition switch and projects from the front plate thereof, through the switch, and is secured to the rear cover of said switch. The bearing has a chamber 44, wherein a resilient element, preferably a coil spring 45, is positioned, which normally has the interior wall of the chamber as one of its abutments, and the washer 46, which is pinned to the rod 42, as its opposite abutment. The function of this spring is to assist in maintaining the rod 42 in its outermost or inoperative position. The rod 42 is provided with a reduced threaded portion 43^a, shown in dotted lines, which is screwed into an internally threaded bore, formed in one end of the rod 47. By referring to Fig. 8, this structure will be clearly understood. Between the rods 42 and 47, there is secured an arm 49, (see Figs. 7 to 10). This arm has an enlarged portion 50, provided with an aperture 51, which will just fit over the reduced threaded portion of the rod 42, but which is of less diameter than the normal diameter of said rod. The opposite ends of this arm are bifurcated as at 52, one end being adapted to engage with the shank 53 of the controlling element 54, which, in the present instance, controls the single spark type of ignition, of either the battery or magneto type, such as has been described in the co-pending application of Charles F. Kettering and William A. Chryst, filed November 20, 1912, Serial No. 732,483. The opposite end of said arm 49 engages with the controlling element 56, operable to establish the vibrating spark type of ignition.

It will be noted from an inspection of Fig. 7, that the switch shown therein has the controlling element for the vibrating spark type of ignition, positioned diametrically opposite from the controlling element of the single spark type ignition, and this permits the use of a straight angle arm, such as is shown in Fig. 9. However, if the controlling element of the vibrating spark type of ignition is positioned at 90 degrees from the element which controls the single spark system of ignition, as is shown in the switch illustrated in Fig. 2, the conformation of the arm will be as is shown in Fig. 10. The controlling elements of the ignition switch, as is clearly shown in Fig. 7, will be normally maintained in their inoperative position, by means of the springs 60. The operative end of the controlling element 54 is provided with a beveled flange 62 and the annular flange 63, thus leaving a reduced portion therebetween. The arm 49, carried by the main operating member, engages the shank of the controlling element 54, directly

to one side of the annular flange 63, so that when the main operating element is pressed in, the arm 49 will engage with this flanged portion and thus move the entire controlling element 54, in such a manner that the operative end of said controlling element may engage with the contact plate 65, and force the same into engagement, or contact, with the plate 66.

Concurrently with the above operation, 75 the detent element 67 will be forced out of its normal position, until said flange has passed by the detent, at which time said detent will be returned to its normal position, by means of the spring 68. Now, 80 when the detent returns to its normal position, a portion thereof will engage the controlling element between the beveled flange 62 and the annular flange 63, and thus maintain said controlling element in position to close the contacts 65 and 66, until such time as the detent is moved backwardly to release said element. On the controlling element 56, there is no beveled flange, such as has been described in connection with 85 the controlling element 54, and therefore, the detent element will have no locking effect, relative thereto. However, this element 56 has an annular flange 70, against which one end of the arm 49 will abut, when 90 the rod 42 is pressed inwardly and thus the controlling element 56 will be carried into position to operate the contact elements which control the establishment and disestablishment of the vibrating spark circuit, 95 for such a time as the operator maintains said element in depressed position.

Inasmuch as the bearing 43, through which the rods 42 and 47 extend, is of tubular conformation, it is necessary to slot said bearing as at 80, in order to permit the assembling of the arm 49, relative to the main operating member and to facilitate and permit the operation of said arm in accordance with the movement of the main operating member. The free end of the rod 47 is provided with a cam projection 90, which, controls the closing of the contact plates 91 and 92, embodied in the slow initial starting circuit of the motor or dynamo-electric-machine, as will be described hereinafter.

Referring to the diagrammatic view, the initial starting circuit may be traced as follows: from the battery 29, current will flow through the wire 29^a, across the switch plates 92 and 91, thence through the conductors 94 and 10, across the generator brushes 98 and 97, thence through the wire 93, across the conductive elements 26^a, 26 and 27 of the controlling switch, and back to the battery, via wire 28. This is substantially the same arrangement as is shown in the co-pending application of Charles F. Kettering, filed September 19, 1912, Serial No. 721,237, so far as relates to the supplemental 130

circuit arrangement with the generator windings but it will be obvious that this circuit arrangement can be connected with slight changes to the motor winding with 5 equal facility, and accomplish exactly the same purpose. Of course, this initial starting circuit only passes sufficient current to the armature of the electric machine to permit the same to rotate slowly as a preliminary 10 to the shifting of the connections between the engine and the starting device.

From the description thus far given of the present invention, it will be seen that by what may be termed the initial operation 15 of the main operating member, the contacts 91 and 92 will be brought together to close the circuit for effecting the slow initial movement of the starting device and the controlling elements of the ignition system 20 will be brought into such position as to establish ignition of one or more types. Now, it is this same operating member which, upon further movement, is adapted to effect the shifting of the connections between 25 the starting device and the engine, and also the shifting of the electrical connections between the starting device and the storage battery. However, as has been explained heretofore, it is advisable that the closing of the circuit to effect a slow movement 30 of the starting device and the shifting of the connections between the engine and the starting device; and the changing of the electrical connections between the starting device and the battery, take place with certain predetermined timed relation to 35 each other. It will also be obvious that the circuit connections between the starting device and battery should not be shifted until 40 after the starting device has been connected up to the engine, and it is therefore extremely advisable that the coupling of the engine and the starting device together, take place previous to the shifting of the battery 45 connections.

The arrangement for shifting the coupling mechanism previous to the changing of the battery connections, has already been 50 fully described and illustrated in the co-pending application of Charles F. Kettering filed June 15, 1911, Serial No. 633,443, and it will therefore not be described in detail in the present case.

In order that the main operating member 55 may be moved initially to establish the circuit for effecting the slow initial movement of the motor, previous to the shifting of the coupling mechanism between the engine and starting device, there is provided an elongated slot 105, formed in the free end of the rod 47, wherein the pin 95 is positioned. It will therefore be seen that this main operating member may be moved a distance equal to the extent of the slot 105, 60 during which movement the contact plates

91 and 92 will be brought together and the slow initial circuit established. The pin 95, which has been described as being positioned in the slot 105, is carried by the lever 100 which is so pivoted that a slight movement imparted by the main operating member to one end thereof, will effect a much greater movement of the opposite end of said lever, which end is secured to a yoke member 101, and is connected to the coupling mechanism in a manner substantially the same as that described in the co-pending application of Charles F. Kettering, filed June 15, 1911, Serial Number 633,443. Now, as soon as the main operating member has been moved to the point where the pin 95 is engaged with the wall, at the end of said slot, the lever 100 will be picked up and shifted by any further movement of the main operating member and thus will cause the shifting of the coupling mechanism, and the consequent connecting up of the motor and engine. Incidental to the movement of the coupling mechanism or gearing 110, the rod 113 will of course be 70 shifted, which will also move the rod 114. This rod 114 is connected with the movable member 26 of any suitable switch mechanism 25, contained within the casing 115, and which controls the electrical connections 75 between the battery and electric machine.

Referring to the diagrammatic view in Fig. 1, it will be seen that there are three operative controlling elements for the ignition switch, namely, 56, 120 and 54, which control respectively, the vibrating spark system, the magneto system, and the single spark type of battery ignition. Any of these elements may be moved independently of the other, to establish a different type of ignition, independent of the movement of the main operating member, which controls the starting system, and incidentally, the ignition systems. Of course, if it is desirable, the member 49 may be constructed 100 with three arms, so arranged that each of said arms will engage with one of the controlling elements of the ignition system. Under these conditions, of course, the magneto circuit and the single spark type of battery ignition would be brought into operative position by the operation of the main operating member and would be maintained in position to establish said systems by the co-operation of the spring controlled 105 detent. At the same time, the controlling element for the vibrating spark type of ignition would also be brought into position to establish this system, incidental to the operation of the main operating member, but this latter controlling element would not be effected by the latching detent and would return to its normal position, as soon as the pressure was released from the main operating member and said member 110 120 125 130

turned by the spring 45 to its normal position.

In the co-pending application of Charles F. Kettering and William A. Chryst, filed November 20, 1912, Serial No. 732,483, there is shown, described and claimed a releasing and locking mechanism, which is adapted to operate relative to the spring controlled detent, to release any of the buttons or controlling elements of the ignition system which are held in position to establish the various ignition circuits or system, and permit the same to be returned to their inoperative position, by means of the spring member 60. In the present invention, this locking device retains certain of the functions which it had in connection with the subject matter of the co-pending application of Charles F. Kettering and William A. Chryst, filed November 20, 1912, Serial No. 732,483, and in addition, it has the function of preventing the operation of the main operating member, when said locking device is in position to lock the ignition controlling elements in their inoperative position.

In the form shown in the drawings, the locking and releasing button 150 is capable of a reciprocating movement and also of an oscillatory movement. However, the normal position of the spring pressed plunger 151 prevents the oscillatory movement thereof, except when the key element 152 has been inserted in the button 150, so as to depress the plunger element 151, out of engagement with said button. This locking and releasing element 150 comprises a cylindrical member 156, having segments at one end thereof, cut away so as to leave the projection 153, while the face of said cylindrical member, adjacent to one of the segmental cuts, is beveled as at 154. Normally, this controlling element 150 is so positioned that the beveled face 154 of the cylindrical member 156 lies adjacent to the edge of the spring controlled detent, and it will be seen that upon pressing in said releasing element, that the detent will be engaged by said beveled portion, and gradually forced out of its normal latching position. Thus, the reciprocal movement of this locking and releasing element may be defined as one of its "releasing movements". However, when the key 152 is inserted in said element, and the same is turned, the spring controlled detent will be engaged by the projection 153, at the end of the cylindrical member 156. Thus, the detent element will first be forced out of its normal latching position into a releasing position, and secondly, will be permitted to return to such a position that a portion of the detent will underlie the longitudinal axis of each of the controlling elements or buttons, and thus prevent further operation thereof, until this releasing button has been turned back

to its normal position, during which operation, said detent will be forced into a releasing position, relative to any of the buttons which may have been locked in. It will be understood that the locking effect of this detent element is made possible by making the segmental cuts at the end of the cylindrical element 156 unequal, so that when the button is in position to permit the locking effect of the detent, the said detent will be moved over beyond its normal home position.

The foregoing description sets forth one form of embodiment of the present invention, but it is to be understood that no limitation is intended by the description or illustration of the form of the invention herein disclosed but that applicant reserves the right to make whatever changes and alterations in the present invention as may come within the scope of the appended claims.

What I claim is as follows:—

1. In a system of power distribution and control, the combination with an engine, of a starting and ignition system therefor; said starting system being normally disconnected from the engine and a main operating member operable to effect the coupling of said starting system and engine together for starting purposes, and to bring the ignition system into operation to furnish ignition for the engine.

2. In a system of power distribution and control, the combination with an engine, of a starting device and a plurality of ignition systems of different types therefor; and a controlling element operable to bring said starting device and a plurality of the ignition systems into operation to start the engine and to concurrently furnish different types of ignition therefor.

3. In a system of power distribution and control, the combination with an engine; of a starting device and a plurality of ignition systems therefor; a controlling element operable to bring said starting device and a plurality of the ignition systems into operation to start the engine and to furnish ignition thereto respectively; and means for maintaining one of said ignition systems in operative condition, when said controlling element returns to its normal position.

4. In a system of power distribution and control, the combination with an engine; of a starting device and a plurality of ignition systems; of coupling means for connecting the engine and starting device together; and a main operating member for establishing said ignition systems, and operating said coupling mechanism to connect the engine and starting device together, concurrently.

5. In a system of power distribution and control, the combination with an engine, of a starting device and a plurality of igni-

- tion systems for starting and igniting said engine; of coupling means for connecting the engine and starting device together; a main operating member for establishing said ignition systems and operating said coupling mechanism to connect the engine and starting device together; and independent elements for controlling said ignition systems, operable independently of or concurrently with said main operating member.
6. In a system of power distribution and control, the combination with an engine, and a starting device therefor; of a plurality of 15 ignition systems embodying a common switch having controlling elements, whereby different types of ignition may be brought into operation; and a main operating member for controlling said starting 20 system and adapted to operate certain of the controlling elements of the ignition switch, when actuated to bring the starting device into operation.
7. In a system of power distribution and 25 control, the combination with an engine, of an electric machine capable of operation as a motor; coupling means for connecting said machine and engine together; a source of current; circuit connections between the 30 machine and source of current; of an ignition system embodying a switch for establishing and dis-establishing said ignition system; and a main operating member operable to close one of the circuit connections 35 between the electric machine and the source of current, whereby said machine will be operated slowly as a motor, said operating member having provisions for operating said ignition switch, to furnish ignition to 40 the engine.
8. In a system of power distribution and 45 control, the combination with an engine and a starting device therefor; means for connecting the engine and starting device together; an operating member for actuating said coupling means; and means for locking 50 said main operating member in inoperative position.
9. In a system of power distribution and 55 control, the combination with an engine, of a starting device therefor; of coupling means for connecting the engine and starting device together; a means for imparting a slow initial movement to the starting device, to facilitate the operation of the coupling means; and a locking means operable to prevent the operation of the means for imparting a slow initial movement.
10. In a system of power distribution and 60 control, the combination with an engine, of a starting device and an ignition system therefor; a controlling element having connecting devices for bringing said starting device and the ignition system into operation to start the engine and to furnish igni- 65
- tion therefor respectively; and means for maintaining the ignition system in operation when said controlling element returns to its normal position.
11. In a system of power distribution and 70 control, the combination with an engine, of a starting device and ignition system therefor, said starting device being normally disconnected from said engine, of coupling means for connecting the engine and starting 75 device together; and a main operating member for establishing said ignition system, and operating said coupling mechanism to connect the engine and starting device together.
12. In a system of power distribution and 80 control, the combination with an engine, of a starting device and an ignition system therefor; a controlling element having connecting devices to bring said starting device and ignition system into operation to start the engine and to furnish ignition thereto respectively, one of said connecting devices being operable independent of said 85 controlling element for discontinuing said ignition system.
13. In a system of power distribution and 90 control, the combination with an engine, of a starting device and an ignition system therefor; a controlling element having connecting devices to bring said starting device and ignition system into operation to start the engine and to furnish ignition thereto respectively; means for maintaining said ignition system in operative condition, after 95 said controlling element returns to its normal position; and means independent of said controlling element for cutting out said ignition system.
14. In a system of power distribution and 100 control, the combination with an engine, of a starting device and ignition system therefor; and an operating member having connecting devices to mechanically connect said starting system and the engine together for starting purposes and to bring the ignition system into operation, and adapted to break said mechanical connections between the starting device and engine, when the engine 105 becomes self-actuating, without interfering with the continued operation of the ignition system.
15. In a system of power distribution and 110 control, the combination with an engine, of a starting device and ignition system therefor; a main operating member for said starting device; independent controlling elements for the ignition system; of a locking device for locking the ignition controlling elements in inoperative position; and connections between the ignition controlling elements and the main operating member for preventing the operation of the main operating member when the ignition controlling elements are in locked position.

16. In a system of power distribution and control, the combination with an engine, of a starting device therefor; an ignition system of the vibrating spark type; and a controlling member having connecting devices to bring said starting device and ignition system into operation to start the engine and to release the starting device from the engine and render the ignition system ineffective when the engine becomes self-actuating.

17. In a system of power distribution and control, the combination with an engine, of a starting device therefor; ignition systems of the vibrating and single spark type; and a controlling member having connecting devices operable to bring said starting device and both ignition systems into operation to start the engine.

18. In a system of power distribution and control, the combination with an engine, of a starting device therefor; ignition systems of the vibrating and single spark type;

and a controlling member operable to bring said starting device and both ignition systems into operation to start the engine, and to release the starting device and vibrating spark system when the engine becomes self-actuating.

19. In a system of power distribution and control, the combination with an engine, of a starting system normally disconnected therefrom; an ignition system; and a main operating member operable to impart an initial movement to facilitate connecting the starting system and engine together, and to bring the ignition system into operation, and to then effect the operation of the starting system for starting purposes.

In testimony whereof I affix my signature 40 in the presence of two subscribing witnesses.

FORREST B. MACNAB.
